TREE-TYPE DISPLAY RACK

Harry C. Robinson and Thomas F. Challis, Chattanooga, Tenn., assignors to American Manufacturing Company, Chattanooga, Tenn.

Application January 7, 1941, Serial No. 373,500

7 Claims. (Cl. 248—158)

This invention relates to a stand or rack for supporting and displaying merchandise, as for example bottled beverages and like commodities, and an object of the same is to provide a knock-down tree-type display stand or rack made up of units which in the main may be readily manufactured from wire or rod stock and which at the same time ensure a firm and stable support for the merchandise.

More specifically, the invention contemplates a tree-type display stand or rack embodying a plurality of shelves or trays assembled in knock-down relation to a central supporting column and a base member, the shelves and base member being made up principally of wire rod members bent into suitable shape and connected by welding, the entire rack being capable of manufacture at a relatively low cost and at the same time being unusually strong and rugged.

The foregoing and other objects and advantages will become apparent in view of the following description taken in conjunction with the drawings, wherein:

Fig. 1 is a view in perspective elevation of a rack constructed in accordance with the invention;

Fig. 2 is a sectional plan view of one of the shelves or trays taken substantially on the line 2—2, Fig. 3;

Fig. 3 is a view in elevation of Fig. 2;

Fig. 4 is a plan view of the base member;

Fig. 5 is a view in elevation of Fig. 4; and

Fig. 6 is a sectional fragmentary detail view illustrating how the base member provides a socket for the central post or column.

One purpose for which the improved stand or rack has been devised is for supporting and displaying bottled beverages in cartons, and it has been so illustrated in Fig. 1. The rack consists essentially of a base, a central post and a plurality of shelves or trays which may be packed and shipped in knock-down relation and easily set up at the store or other place where the rack is to be used. The base member and shelves or trays are made up principally of wire rod stock while the central post or column consists of a length of pipe stock socketed into the base with the shelves detachably mounted in vertical spaced relation thereon.

First describing the base and which is best shown in Figs. 1, 4, 5 and 6, this comprises legs 10, 10' and 11, 11'. The legs 10, 10' and 11, 11' constitute pairs with each pair made from a single length of wire or rod stock having an elongated rectangular shape in plan view with a flat or

horizontal top portion 12 from which point the wires are bent at an angle or incline downwardly with the lower closed ends of the rectangles forming feet 10a and 11a and the free ends of the wires or rods brought back to the flat base 12 and overlapped and welded at 13 forming a rectangular socket 14. One free end of each one of the rectangular rods or wires which go to make up the legs and feet of the base is bent downwardly to provide clamping prongs 15 and 16 for a purpose which will be presently described.

The pairs of legs 10, 10', 11, 11' are thus made up of two separate pieces of wire or rod stock with each piece doubled upon itself in an elongated generally rectangular pyramidal fashion and the two pieces welded to one another on the horizontal or flat top 12.

To reinforce the base, individual lengths or pairs of wires 18 and 19 are positioned with their opposite free ends on the inside of and welded to the lower closed ends of the legs 10, 10' and 11, 11' which form the feet 10a, 11a. One of these pairs, as here shown the wires 18, has the central portion bent upwardly at a point in substantially vertical alignment with the socket 14 providing a socket boss 20; and the wire lengths 19 straddle said boss and are welded to the lengths 18 on each side thereof, as indicated at 21. Preferably but not necessarily the reinforcing wire lengths 18 and 19 are of smaller gauge than the legs 10, 10' and 11, 11'.

A central column 22 is provided and is made up of a length of pipe with the lower end inserted through the socket 14 and over the socket boss 20, note particularly Figs. 1 and 6. To ensure against looseness of the pipe relative to the base, the prongs 15 and 16 are provided and arranged to be bent inwardly and frictionally engage the pipe under tension and preferably at one side 40 of the latter. This gives in effect a three-point contact. This feature is of advantage particularly in view of the fact that commercial pipe does not run uniform in size or wall thickness, so that if there would be no adjustment of the 45 socket opening, the connection would be loose and rickety and, in fact, it would be difficult to have a uniform fit in the initial assembling operation.

The individual trays or shelves are best shown 50 in Figs. 2 and 3 and are indicated at 23, 23' and 24, 24'. The tray or shelf 23, 23' is made up of a single piece of wire bent in substantially rectangular form and reinforced by cross rods 25, while the shelf 24, 24' is also made up of a single 55 piece of wire bent in the form of a rectangle

and reinforced by cross rods 26. The opposite ends of each shelf are preferably bent upwardly, as at 27, note particularly Figs. 1 and 3, to provide retaining means for the cartons or other packages which may be disposed on the shelves. The rectangular wire which makes up the shelf 24, 24' overlies the wire of the shelf 23, 23' and is welded thereto as indicated at 28.

To support the wire framework which makes up the shelves and to also provide a means for securing the shelves to the central post or pipe 22, angle brackets 30 and 31 are provided, each preferably consisting of a strip of metal of generally U-shaped form with the brackets arranged back to back and welded to one another in the regions indicated at 32. At the central portion of the substantially H-shaped member formed by the brackets 30 and 31, the strips are bent reversely to provide a socket opening 33 but leaving a space 34 in the region of the opening. To secure the brackets to the pipe 22, the latter is formed with a transverse hole and a screw 35 is projected through the strips at the point where they are bent outwardly to form the socket 33, the screw 35 being provided with a wing nut 36.

Due to the fact that the brackets 30 and 31 are welded together at the point 32, when the nut 36 is tightened down, the metal which defines the socket 33 is caused to grip the pipe under tension, thereby holding the shelf or tray unit tightly to the central post or pipe 22. If these strips were not welded together, the clamping pressure exerted by the nut 36 and bolt 35 would bend the socket to the contour of the pipe, which would result in a loose or rickety fit. This spring-clamping effect is enhanced by the top frame being welded at right angles to the bottom frame at the points indicated at 28 and also to the bracket strips at 37 and 38, note Figs. 2 and 3, the wire being bent downwardly at the weld 38 to avoid throwing the top tray out of alignment. This arrangement of the brackets and wire frames also provides maximum supporting capacity with a minimum number of wires.

To assemble the parts of the rack, the pipe 22 is simply socketed into the base by inserting the pipe through the socket 14 with the hollow end of the pipe engaging the boss 20, it being understood that the downwardly projecting clamping prongs 15 and 16 are first bent inwardly sufficiently to engage the pipe under tension. This results in a firm and rigid connection between the upright post 22 and wire base. The trays or shelves are then mounted on the post 22 and the wing nuts 36 tightened to hold the shelves rigidly to the post.

The upper end of the post 22 is split or formed with a notch 39 to receive a sign 40.

To knock down or disassemble the rack, it is only necessary to unscrew the wing nuts 36 and remove the shelves or trays and then pull upwardly on the post 22 to remove it from its base.

The rack may be shipped in a compact bundle with the shelves nested, and may be easily and quickly set up at the point of use; it is strong and durable and is capable of supporting a heavy load without danger of sagging or becoming overbalanced.

It will be understood that no attempt has been made herein to enumerate all the advantages of the improved rack, and further, that certain changes in construction and design may be adopted without departing from the spirit or scope of the invention as defined by the appended claims.

We claim:

1. A rack or stand comprising, in combination, a base made up of wire or rod stock bent to form a plurality of legs projecting downwardly and outwardly at angles to one another with the wires at the central portion of the base arranged in cross-connected relation to form a resilient substantially vertical socket, a central column or post having its lower end inserted in said socket with the wires of the socket engaging the post under tension.
2. A rack or stand comprising, in combination a base made up of wire or rod stock bent downwardly and outwardly from a substantially planar top portion in a series of generally rectangular shapes to provide supporting legs and feet, the wires at the top portion being cross connected to provide a socket opening with the free ends of the wires bent at angles to the opening to provide resilient prongs within the area of the socket, and a central column or post projected into said socket with the prongs engaging the post under tension.
3. In a tree-type rack or stand for supporting and displaying merchandise and the like, a base made up of wire or rod stock bent downwardly from a substantially planar top portion to provide legs and feet for the base, the wires at said top portion being crossed at substantially right angles to one another and welded to provide a socket opening, said wires having downwardly projecting free ends forming prongs within the socket area, said legs being reinforced by cross-connecting wires certain of which are bent upwardly to provide a boss, and a central post or column having a hollow lower end projecting through said socket into engagement with said boss with said prongs frictionally engaging said post.
4. In a tree-type rack or stand for supporting and displaying merchandise and the like, a wire base made up of separate lengths of wire or rod stock shaped to provide a substantially planar top portion and a series of downwardly and outwardly projecting elongated substantially rectangular leg and feet portions, the free ends of the wire lengths being brought back and terminating at the top of the base and arranged to form a socket with certain of said ends bent downwardly to provide resilient prongs within the area of the socket, reinforcing wires cross-connecting said feet with certain of said latter wires bent upwardly at an intermediate point in alignment with said socket to provide a boss, and a post in the form of a hollow pipe length or section having one end thereof projected through said socket and into engagement with said boss with said prongs resiliently engaging the side walls of the post under tension.
5. In a tree-type rack or stand for supporting and displaying merchandise and the like, a base made up of a pair of individual lengths of wire or rod stock, each length being shaped in the form of an elongated rectangle with a substantially planar central portion and opposite downwardly and outwardly projecting portions, the members thus shaped being arranged at substantially right angles to one another with the wires of the planar portion crossing at right angles and welded to provide a central substantially vertical socket and the downwardly and outwardly projecting portions forming legs and feet for the base, the free ends of the wires being brought back to the planar portion with at least two of said ends bent downwardly within

the socket to provide resilient prongs, a series of substantially straight wire lengths crossed at right angles in the plane of the feet for reinforcing the legs and feet and having their opposite ends welded to said feet, the intermediate portion of certain of said reinforcing lengths being bent upwardly to form a boss, and a central post or column in the form of a hollow pipe section having its lower end projecting downwardly through said socket opening and onto said boss with said prongs resiliently engaging the post under tension.

6. In a display rack or stand of the class described, an upright post and a base for supporting the post, said base being made of wire or rod stock bent in the shape of leg members with broad lower extremities, said leg members converging at a central point one leg member being disposed relative to another leg member in substantially right angular relation with the wire at such point shaped to provide a socket opening adapted to receive the lower end of said post, and a plurality of prongs projected from the wire

around said opening, said prongs extending substantially vertically but converging slightly inwardly into the socket area a substantial distance below the socket opening to permit the post to be 5 readily projected into the socket opening with the prongs frictionally engaging the post under tension and holding the latter stable in the socket.

7. In a display rack or stand of the class described, an upright post and a base for supporting 10 the post, said base being made of wire or rod stock bent in the shape of leg members converging at a central point, the wires of one leg member overlying the wires of another leg member in substantially right angular relation and 15 spaced to provide a socket opening, reinforcing members cross-connecting the lower extremities of said leg members, said reinforcing members being shaped to engage the lower end of the post or column and coact with the said socket to hold 20 the post in stable position in the socket.
